UNITED STATES PATENT OFFICE.

AUGUST DAUBER, OF BOCHUM, GERMANY.

HELICAL LOADING APPARATUS.

SPECIFICATION forming part of Letters Patent No. 431,650, dated July 8, 1890.

Application filed January 26, 1889. Serial No. 297,741. (No model.) Patented in France July 30, 1888, No. 192,106; in Belgium August 6, 1888, No. 61,677; in England September 23, 1888, No. 11,946; and in Germany November 19, 1888, No. D, 3,516.

To all whom it may concern:

Be it known that I, AUGUST DAUBER, merchant, subject of the Emperor of Germany, and resident of Bochum, Province of Westphalia, have invented a new and useful Improvement in a Helical Loading Apparatus for Briquettes, Coal, and other Goods on Board Steamers and in Warehouses, (for which I have received Letters Patent in France, No. 192,106, dated July 30, 1888; in Belgium, No. 61,677, dated August 6, 1888; in England, No. 11,946, dated September 23, 1888, and in Germany, No. D, 3,516, published November 19, 1888;) and I do hereby declare that the following is a full, clear, and exact description of the invention, which will enable others skilled in the art to make use of the same.

The means provided for loading coal on board ship and for bringing it down in the lower compartments (the coal-bunkers of a steamer,) consist of an open cylindrical shaft, through which the coal is thrown down, and which also serves for ventilating purposes. The height through which the coal thus falls is rather considerable, and therefore a comparatively large quantity of coal is broken and turned into dust and shingle and thus loses in quality as a combustible. Briquettes could not stand such a rough treatment, and therefore, they must be excluded from the use on board steamers or else they must be loaded in some other manner, which, of course, again increases the expense, for which reason this artificial fuel is not used as much as it deserves, notwithstanding its evaporating quality makes it highly applicable as fuel for boilers, and by their form briquettes recommend themselves better for being stored on board steamers than any other sort of fuel.

Now, in order to facilitate the loading of briquettes so that they can be loaded without requiring any special care and without being exposed to the danger of being broken, I have invented the helical loading apparatus shown in the accompanying drawings and described hereinafter.

I beg to observe that the apparatus is adapted as well for loading all other goods requiring careful treatment in having to be

brought from higher compartments to a place 50 lower down.

In the drawings, Figure 1 is a vertical section through the helical loading apparatus; Fig. 2, a horizontal section; Fig. 3, an outside view of part of the arrangement with an outlet door and a discharge or sloping plane in enlarged scale; Fig. 4, a horizontal section through Fig. 3; Fig. 5, a vertical section through Fig. 3, showing the door shut. Fig. 6 is a vertical section through Fig. 3, showing 60 the door open. Figs. 7 to 11 show details of construction. Fig. 12 is a side view of the device.

My helical loading apparatus consists of a shaft or hollow cylinder A of twenty-four to 65 thirty inches in diameter, more or less, as may be desired, and of an inner cylindrical core B. Into the annular space thus formed between the two cylinders A and B, I place in a convenient manner the screw C, running from the 70 top to the bottom. The pitch or the angle of inclination of this screw is such that this angle is a little larger than the angle of friction of the goods to be loaded by means of the helical loading apparatus.

At the top the screw-surface adjoins a sort of a table or a jetty on the deck of the vessel on which the briquettes are stored and from which they are simply pushed into the shaft, and then they glide down the screw-surface 80 at a comparatively high speed and reach the bottom or their place of destination without being broken, the inside surfaces of the screw and of the cylinder being all smooth.

The screw is made of several single pieces 85 ranged together, as shown by Fig. 10, and lying at the sides on angle-irons which support them, as shown by Figs. 1, 5, and 6, so that they can be taken to pieces easily and withdrawn from the shaft, that this may serve for ventilating purposes, as usual.

In order to be able to take out briquettes or other goods at various places from the shaft and at various heights, I arrange in such places the inclined planes D, which form the 95 tangential continuation of the screw, and upon which the goods coming down in the shaft are carried further to the places desired. At

those places I make doors E in the circumference of the cylinder A, which can be drawn up and down for being opened and closed. With these doors there are connected dia-
5 phragms F let into the screw-surface and forming by their top part of the screw when the doors are shut, but stopping the continuity of the screw or crossing the passage when the doors are opened and pulled upward. These
10 diaphragms are also so arranged that they form the tangent to the inner cylinder B, and the briquettes, &c., coming down in the shaft in their spiral way, which, by nature, have the tendency to go off in a tangential
15 direction, will follow willingly the direction given them by the diaphragm without striking against it or being thrust against it, and since all adjoining surfaces are quite smooth and flat, the briquettes are not hurt by any
20 shocks, and even the most fragile goods can thus be loaded and brought quickly from the deck of vessels to the lower compartments by means of my helical loading apparatus.

The sloping or inclined planes D can be
25 provided with an endless web and movable rollers, as shown by Figs. 1 and 2, at the bottom on the right side, in which case the slope of the plane need not absolutely be steeper than the angle of friction of the goods to be
30 loaded. It may even be less.

I am aware that loading arrangements based on the use of an Archimedean screw have been used before, and I therefore do not claim such a design broadly; but

What I do claim as my invention, and desire 35 to secure by Letters Patent, is—

An apparatus for loading coal, briquettes, and other goods of a fragile nature from the deck of steamers into the coal-bunkers and lower compartments, or for bringing such 40 goods from the upper localities in warehouses to lower ones, the same consisting of a cylindrical casing A, an internal cylinder B, and a screw-shaped guideway C, laid in the annular space between the cylindrical casing A 45 and cylinder B, the casing being provided at various places with outlet-doors E, and with sloping planes D, adjoining the screw-shaped guideway and the outer cylindrical casing in a tangential direction, and in combination 50 with the doors E, diaphragms F, crossing the screw-shaped guideway in a line forming the tangent to the inner cylinder B, and being so arranged that when the doors are opened they direct the goods to the outlet, and when the 55 doors are closed the diaphragms are sunk below the screw, their top forming part of the surface of the latter.

In testimony that I claim the foregoing as my invention, I have signed my name in presence of two witnesses this 6th day of December, 1888.

AUGUST DAUBER.
